UNITED STATES PATENT OFFICE

FRED L. MILLS, OF OAK PARK, ILLINOIS, ASSIGNOR TO MILK NOVELTY COMPANY, OF CHICAGO, ILLINOIS, A CORPORATION OF ILLINOIS

TARGET PRACTICE VENDING MACHINE

Application filed July 16, 1928. Serial No. 292,927.

This invention relates to target practice vending machines of the general type shown in my prior Patent No. 1,594,066, dated July 27, 1926, and has for its principal object the provision, in such a machine, of a greater variety of targets, together with means for changing the designation of said targets, or certain thereof, to thereby vary the rewards obtainable for hitting particular targets.

A further object of the invention is the provision of a novel combination of vending mechanism and target practice devices whereby the coins used in the target practice serve to operate the vender to always deliver a predetermined value in mints, gum, or other articles, and are then available for use in a game of skill which enables the customer to obtain additional rewards or prizes, or to compete with others for points indicated by targets at which the coins used for the purchase of the gum or other articles may be driven before being deposited in the coin receptacle or receptacles. Obviously, this stimulates the use of the vending machine and increases the receipts obtained therefrom.

Other objects and advantages of the invention will be apparent as it is better understood from the following description, which, taken in connection with the accompanying drawings, discloses a preferred embodiment thereof.

Referring to the drawings,

Figure 1 is a front elevation of a machine in which my invention is embodied;

Fig. 2 is a side elevation thereof;

Fig. 3 is a top plan view of the machine;

Fig. 4 is a rear elevation with the back wall removed and the lower part of the casting broken away for economy of space;

Fig. 5 is an interior view of the coin slot, showing the coin-actuated lever of the vending mechanism and the driver employed to

impel the coins towards the targets of the machine;

Fig. 6 is a sectional view, taken substantially on the section line 6—6 of Fig. 5;

Fig. 7 is a transverse sectional view taken substantially on the section line 7—7 of Fig. 4;

Fig. 8 is a detail view of the lower part of the merchandise compartment and of the vending mechanism, parts of which are shown in their position after operation of the coin mechanism and just prior to operation of the ejector;

Fig. 9 is a detail view of certain of the parts shown in Fig. 8, the position thereof being that assumed after operation of the ejector;

Figs. 10 and 11 are detail views of the coin-actuated controlling devices of the vending mechanism, showing the operation of the parts;

Fig. 12 is a broken plan view of the mechanism for rotating the legend-bearing cylinder associated with the coin pockets in the lower part of the machine, the view being taken substantially on the plane 12—12 of Fig. 13;

Fig. 13 is a front-to-back sectional view taken substantially on the line 13—13 of Fig. 12;

Fig. 14 is a transverse sectional view, taken substantially on the line 14—14 in Fig. 12;

Fig. 15 is a broken plan view, corresponding to Fig. 12 but with the parts shown in different position;

Fig. 16 is a section taken on Fig. 15, substantially along the line 16—16;

Figs. 17 and 18 are similar views, showing succeeding stages in the operation;

Fig. 19 is a sectional view of the coin-ejecting means for the upper coin pockets, or targets, taken substantially on the section line 19—19 of Fig. 4;

Fig. 20 is a horizontal sectional view of

the mechanism shown in Fig. 19, the same being taken substantially on line 20—20 of Fig. 19;

Fig. 21 is a detail view, taken substantially on the plane 21—21 indicated in Fig. 20; and

Fig. 22 is a detail view taken substantially at right angles to Fig. 21, looking toward the left, the normal and projected positions 10 of the ejector being indicated respectively in full and dotted lines.

Referring first to Figs. 1, 2, and 3, it will be observed that the machine is enclosed in a casing comprising an upper part 25, which 15 is relatively narrow from front-to-back, and a lower part 26, which is wider and adapted to have a front wall 27 thereof locked in place by means of a lock 28 (see Fig. 13), the key-hole for said lock being indicated at 20 29 in Fig. 13. This lower part of the casing, as will later appear, is adapted to provide a receptacle for the coins, which accumulate in said receptacle until removed by an authorized person possessing a key. 25 The top of the casing may also be provided with a removable panel 31, provided with a lock, a key-receiving portion of which is indicated at 32, thus providing an opening for filling a merchandise receptacle or compartment identified by the numeral 33 in Fig. 4.

A coin slot is provided in a bracket 34, in which there is an opening 35, through which the coin is adapted to be inserted, the interior construction of this coin slot bracket 35 being illustrated in Figs. 5 and 6, to which reference is now made. Upon insertion of a coin 36, it falls by gravity in the slot 37 to the position indicated in full lines in Fig. 5, in which position it is supported between 40 an arcuate wall 38 of the slot and a stud 39 carried by an arm 41 of a bellcrank lever, which is pivoted at 42 to the slot bracket 34, the other arm 43 of said lever extending through a slot 44 in a side wall 45 of the cabinet and being pivotally connected at 45 to a vertical throw-out lever 47 of the vending mechanism (see Fig. 4). For the purpose of actuating the lever 43, an actuator 48 is provided in the upper part of the 50 coin slot, being pivoted at 49 and adapted to be held in raised position by means of a spring 51, secured at one end to the actuator at 52 and at the upper end to a stud 53 in the upper part of the bracket 34. The 55 actuator, in its rest position, is held in contact with a stud 54 in the bracket 34, a squared top portion 55 of said actuator being in engagement with the lower end 56 of a push rod 57, upon the upper end of which 60 is provided a thumb button 58. Depression of said button 58 moves the actuator downwardly about its pivot 49, as shown in dotted lines in said Fig. 5, and into engagement with the coin 36, which is moved to the first 65 dotted line position shown, thereby turning

the bellcrank lever 41, 43 to the dotted line position and permitting the coin to fall to the second dotted line position in the lower part of the slot. This actuation of the lever 43 produces an operation of the vending mechanism and also deposits the coin in position to be used by the customer for purposes of target practice, as will presently appear. For the latter purpose, the coin is adapted to be forcibly directed through the 70 upper part of the casing by means of a driver 59, which is pivotally mounted at 61, and the central part of which is disposed in an arcuate cut-out 62 in the lower part of the slot bracket 34 so that the customer 75 may actuate the same with his finger, thereby impelling the coin through an upwardly inclined slot 63 in said slot bracket, as indicated by the third dotted line position of the coin in Fig. 5, the coin being thus 80 thrown into the space in the upper part of the casing between a glass front 64 and an intermediate wall 65 (see Figs. 1 and 7).

The coin slot bracket 34 is secured to the side wall 45 of the frame by means of angle 85 members 66 and 67, the latter being formed to provide a housing for the outer part of the lever 43.

Referring now particularly to Figs. 4 and 7 to 11, inclusive, the vending mechanism 90 will be described. As shown, the receptacle 33 is adapted to contain a quantity of candy balls, indicated by the reference character 68, which are adapted to pass in a single row through a discharge chute 69, extending from the lower part of the receptacle 33 at the lefthand side thereof, viewing Fig. 4. The outlet of this chute is disposed above a cylindrical delivery member 71, which is 95 rotatably mounted in ears 72 secured to the inner side of the side wall 45, this cylinder being cut out to provide a pocket 73, into which the candy balls are adapted to be deposited from the discharge chute 69. Said cylinder is adapted to be normally held in 100 the position shown in Figs. 4 and 9 of the drawings, with the pocket 73 opening outwardly through an aperture 74 in the side wall 45 of the casing. It is held in this 105 position by means of an arm 75, pivoted at 76 to the intermediate wall 65 of the frame and having a shoulder 77 at the forward end thereof (see Figs. 10 and 11) adapted to engage a stud 78 upon the inner end of the cylinder 71, said arm being normally held in raised position with the shoulder 77 in engagement with said stud by means of a 110 spring 79, secured at one end to a stud 81 on said arm 75, and at the opposite end to a fixed point 82 on the frame. The cylinder is thus held against the tension of a spring 83, secured at one end to a projection 84 upon the outer end of the cylinder at the periphery thereof, and at the opposite end 115 to a bracket 84' on the frame. 120

It will be observed that the lower part of the member 47 is cut down and beveled, as indicated at 85, and that further towards the end of said member, a lug 86 is provided.

5 Said member 47 is normally held in the full line position shown in Figs. 4 and 10 by means of a fixed stud 87, against which said member 47 is held by means of a spring 88, secured at one end to a stud 89 upon said member 47 and at the other end to the fixed stud 82 in the wall 65. When a coin is inserted and the plunger 57, 58 depressed, the lever arm 43 is raised to the dotted line position shown in Fig. 4, thus lifting the throw-out lever 47, as shown in Fig. 10 of the drawings. This causes the beveled part 85 of said lever 47 to ride upon the stud 87, the member 47 moving to the left as it rises, assuming first the dotted line position shown 15 in Fig. 10 and then the dotted line position shown in Fig. 11, in which it will be noted that the lug 86 on the lower end of said member 47 engages over a stud 91 upon the cylinder locking arm 75. After said lever 43 is released by the coin, the spring 88 draws the lever 47 downwardly, moving the same from the dotted line position shown in Fig. 11 to the full line position shown in said figure, in which it rests against a fixed stud 92 on the intermediate wall 65 of the frame. This action also causes the member 47 to move to the right by reason of the beveled portion 85, which engages the fixed stud 87, thereby causing the lug 86 to disengage the stud 91, the member 75 being retained in the down position, however, by means of a stud 78 on the cylinder, which, upon being released, has been rotated a quarter turn in clockwise direction, viewing 30 Fig. 4. In this position, the pocket 73 in the cylinder is disposed beneath the end of the chute 69 and receives a candy ball 68. The customer may then press a plunger 93, extending through the side wall 45 and having 35 a slotted connection at its inner end at 93' with a link 94, pivoted to a frame lug at 94' and pivotally connected at its upper end with a bar 95, having a pin and slot connection at 96 with an agitator member 97, pivoted at 98 to lugs 99 on the bottom of the receptacle 33 and having a plurality of upwardly projecting pins 101 and a finger 102 extending through the bottom of the candy receptacle. A spring 103 is connected to the 50 end of the member 97 beyond the pivot 98, the upper end of said spring being connected to a hook 104 upon the side wall of the receptacle 33. This spring tends to urge the member 97 downwardly against a stop 105 and actuation of the plunger 93 serves to lift said member, causing the pins 101 and the finger 102 thereon to agitate the candy in the receptacle and to move the balls in a single row through the chute 69, as shown in Fig. 55 4. A guard 106 is provided on the interior

of the receptacle 33, just above the entrance to the chute 69 to prevent clogging of the candy balls at this point.

After the cylinder 71 has been released, in the manner hereinbefore described, through the action illustrated in Figs. 10 and 11 of the drawings, and has turned to position to receive a candy ball in the pocket 73, the customer presses the plunger 93, which turns the lever 94 on its pivot 94' and causes the upper end thereof to engage a pin 107 on the outer end of the cylinder 71 and to turn the latter against the tension of its spring 83 to the position shown in Figs. 4 and 9 of the drawings, thereby delivering the candy to the customer. The cylinder is then immediately locked in this position by the locking arm 75 and so held until another coin has been inserted and the mechanism operated as described.

85 The receptacle 33 is secured to the intermediate wall 65 by means of angle members 108 and 109, shown in Fig. 4. A plurality of apertures 111 are provided in the intermediate wall 65, so that the contents of the receptacle 33 can be seen through the glass front 64 of the machine.

90 As previously stated, the coin 36, after having been used to actuate the vending mechanism, drops to the lower part of the slot and against the pivoted driver 59, whereby it may be driven through the slot 63 and into the narrow space between the glass front 64 and the intermediate wall 65 (see Figs. 1 and 7). A plurality of coin pockets, serving as targets, are provided within this space, the greater number of these being disposed in the lower part of said space and being formed by means of lugs 112, suitably spaced to receive a coin 95 therebetween, the coin, when so inserted, being supported by a pair of movable bars, indicated at 113 and 120 in Fig. 12. These lugs 112, in the present instance, are provided upon the intermediate wall 65, from 100 which they protrude, and adjacent each pocket formed thereby a number, or other legend, is visible through one of a series of windows 114 provided in a housing 115, formed in a horizontal wall part 116 at the top of the lower widened portion 26 of the casing, said housing having a legend-bearing cylinder 117 disposed therein, the latter having pins 118 and 119 projecting from the 105 ends thereof and journaled respectively in lugs 121 and 122 depending from the under side of the horizontal wall part 116 (see Figs. 1, 2, and 12). By means of these numerals, or legends, the customer may select the pocket into which he will attempt to direct the coins, and if he is successful, he may score the number of points indicated by the numeral, or legend, associated with the particular pocket selected.

110 120 125 130 In order to reach one of these pockets, the

coins must enter between ribs 123 and 124, provided upon the wall 65 and of a depth substantially filling the space between said wall and the glass front 64. A plurality of 5 studs 125, 126, and 127 may be provided at the entrance to the space between these ribs, if desired. Coins failing to enter this space are deflected by the ribs to inclined ledges 128 and 129, placed respectively beneath 10 openings 131 and 132, through which such coins pass and drop into the coin receptacle in the lower part of the machine. Even after entering the space between the ribs 123 and 124, the coins may be deflected 15 through one of a plurality of openings, indicated at 133, 134, and 135, beneath which are ledges 136, 137, and 138, extending outwardly substantially to the glass front, so as to deflect the coins through said openings. 20 A plurality of studs 139 are provided in the space between the ribs 123 and 124, said studs being spaced apart sufficiently to permit a coin to pass therebetween and said studs being arranged in staggered relationship 25 to provide a tortuous path for the coins to said pockets between the lugs 112.

Other coin pockets, or targets, are provided in the upper part of the casing, at the left-hand side thereof (see Fig. 1), there being 30 three such pockets in the present instance formed by a plate 141 secured to the intermediate wall 65 by means of screws 142 and 143, the mouth of each pocket being cut away in the form of a C, as indicated at 144, 35 and a stud 145 being provided just beneath the mouth to each pocket, the coin, after entering the mouth of the pocket, being directed by guides 146 and 147 to positions from which they are visible through windows 148, with each of which there is associated a numeral, as shown at 149 in Fig. 1, these numerals being for the purpose hereinbefore indicated in describing the pockets and legend cylinder 117 in the lower part of 40 the casing. Mechanism, to be hereinafter described, is provided to release the coins from their positions behind the windows 148 and to cause the same to fall into the coin receptacle, but it will here be noted that the 45 coins are presented to view after they have entered the pockets, so that the results of the play may be observed and so that the use of slugs, of spurious coins, may be detected. The coins in the lower pockets between the 50 lugs 112, which pockets are identified by the reference character 151, are also visible prior to the time that they are discharged into the coin receptacle by mechanism which will next be described.

55 Referring to Fig. 13, the position of the coin 36 in one of the pockets 151 will be observed, it being apparent that the coin at this time is supported by the bars 113 and 120. The form of these bars is illustrated 60 in Fig. 12 of the drawings, from which it

will be noted that a plurality of slots 152 are provided in the bar 113 and a plurality of slots 153 are provided in the bar 120, these slots being of sufficient length to permit the passage of a coin therethrough, but the slots of the two bars being normally arranged in staggered relationship, so that narrow grids 154, separating the slots in these bars, are normally arranged in the position shown in said Fig. 12 and in Fig. 14 of the drawings, in which position it will be noted that the coin 36 is prevented from passing beyond said bars or plates 113 and 120 until they are moved into registration. It will be observed that the plate 113 is urged toward the left, viewing Fig. 12, by means of a spring 155, secured to a lug 156 on said plate and to a stud 157 on the under side of the horizontal wall 116 of the casing and that the plate 120 is urged toward the right, viewing Fig. 12, by means of a spring 158, secured at one end to a lug 159 on said plate 120 and at the other end to a stud 161 on the under side of said horizontal wall part 116. A hand-piece 162 projects upwardly from the lower plate 120 through an opening 163 in the horizontal wall 116 and is adapted to be operated by the customer. The normal position of this hand-piece and the bar is shown in Fig. 14, which also illustrates the coin in the position assumed thereby when dropped into a pocket 151. Assuming the parts to be in the relationship shown in Figs. 12 and 14, with a coin in the pocket, said handle 162 may be moved towards the left to the position shown in plan and in section, respectively, in Figs. 15 and 16. This brings the slots of the plate 113 and 120 into registration, as clearly shown in Fig. 16, permitting the coin to drop onto a fixed plate 164, which is secured to the frame by screws 165, this plate being slotted correspondingly to the plates 113 and 120 and having narrow grids 166 between the slots upon which the coin is supported in the position shown in Fig. 16. Movement of the hand-piece 162 toward the right, from the position shown in said Fig. 16, serves to return the bar 120 to its normal position, as shown in Fig. 17, and the coin carries the bar 113 toward the right in the manner illustrated in said figure until said coin drops through one of the slots in the plate 164 and thence to the coin receptacle. The plate 113 is then returned to the left by means of the spring 155, but, as will now be described, this movement of said plate 113 to the right serves an additional function, namely that of rotating the legend-bearing cylinder 117 so as to bring a new set of legends into view through the windows 114, thus changing the designations associated with each pocket, or target 151.

160 This is accomplished by means of a lug

167 upon said bar 113, which is adapted to strike a roller 168 upon an arm 169, pivoted at 171 to a depending lug 172 on the under side of the horizontal wall 116, this arm carrying at its outer end a pawl 173, pivoted to a plate 174, which is integral with the arm 169 and turned at right angles thereto. Said pawl 173 has an extension 175 beyond the pivot point 176, which extension is connected by a spring 177 with a stud 178 on said plate 174, thus providing a yielding mounting for the pawl. Said pawl is adapted to engage a ratchet wheel 179, rigidly secured to one end of the cylinder 117 (see Fig. 13) so that upon each upward movement of the pawl 173, said ratchet wheel and cylinder are turned one step in clockwise direction, viewing Fig. 13. As will be apparent from Fig. 12, this brings a new row of numerals into view beneath the windows after each operation.

The plates 113 and 120 are slotted, as indicated at 181 and 182, respectively, and, as has heretofore been explained, the slots 152 and 153 therein are normally out of registration, so that the coins are retained in the position shown in Fig. 14 until the operation just described. After the coin has been transferred to the receptacle, which 30 operation produces the rotation of the legend-bearing cylinder 117, the parts are in position for a succeeding operation.

For the purpose of discharging the coins from the pockets in the upper part of the casing, a pivoted bar 183 (see Figs. 4 and 14 to 18) is provided, the lower end of said bar being urged toward the left, viewing Fig. 4, by means of a spring 184 secured at one end to said bar and at the other end to a fixed stud 185 on the frame. The lower end of said bar is adapted to be moved toward the right, viewing Fig. 4, or towards the left, viewing Figs. 14 to 18, by means of a projecting plate 186 on the bar 120 when 40 said bar is moved from the position shown in Fig. 14 to that shown in Fig. 16 of the drawings. Said bar 183 is pivoted at 187 and the upper end thereof is connected by a link 188 with a projection 189 extending 50 rearwardly from a vertical bar 191, which is rockably mounted in bearings 192 and 193 carried on the inner side of the plate 141. Said bar 191 is held in normal position by means of a leaf-spring 194, secured 55 by a screw 195 to the inner plate of a coin chute 196, which has a plurality of passage-ways therein, as indicated in Fig. 19.

Referring now to Figs. 19 to 22, inclusive, it will be noted that beneath the windows 148 in the upper two coin pockets are inclined members 197, at the side of each of which is disposed a finger 198 carried upon the member 191 and normally in the full line position shown in Fig. 20. When said 60 finger 198 is moved to the dotted line posi-

tion shown in Fig. 20, the coin falls by gravity and is directed by the member 197 into a chute 199, or a chute 201, said chutes being associated, respectively, with the upper and middle pockets. Beneath the 70 lowermost pocket, an inclined surface 202 is provided, adapted to direct the coin from this pocket to a third chute 203, the members 197 and 203 being preferably integral with the plate 141, which is flanged at its edge, as indicated at 204. Obviously, the coins are supported by this mechanism behind the windows 148 until the hand-piece 162 is actuated, which results in not only discharging any coins which may be in the 75 pockets in the lower part of the casing, but also in discharging the coins from the upper pockets by rocking the member 191 and moving the fingers 198 thereon away from supporting relation to the coins.

The operation of the machine has been set forth in the foregoing description, from which it will be apparent that upon insertion of a coin and depression of the plunger 57, the lever 43 will be actuated, thereby 90 raising the throw-out lever 47 to the dotted line position shown in Fig. 4, causing the same to engage the stud 91 on the locking lever 75 of the dispensing cylinder 71, the locking lever being thrown out of locking 95 position upon the descent of said throw-out lever after the coin actuation. The cylinder 71 is thereupon rotated a quarter turn by its spring 83 and a piece of candy drops into the pocket 73. The customer then actuates 100 the plunger 93, turning the dispensing cylinder to position to deliver the candy, which operation also actuates the agitator 97 in the manner hereinbefore described. Furthermore, upon rotation of the cylinder, the locking lever 75 is caused by its spring to 105 assume the locking position shown in Fig. 10 of the drawings and the parts remain in this position until the successive actuation.

The coin, after being inserted, may be driven by the driver 59 toward one of the coin pockets, or targets, and upon being deposited therein, remains in view until the customer actuates the transfer mechanism by means of the hand-piece, or rod, 162. This serves to release the coins, which thereupon drop into a coin receptacle, and also rotates a legend-bearing cylinder 117 so as to present a different set of legends 115 in association with the lowermost pockets, or targets, 161.

It is thought that the invention and many of its attendant advantages will be understood from the foregoing description, and it will be apparent that various changes may be made in the form, construction, and arrangement of the parts without departing from the spirit and scope of the invention, or sacrificing all of its material advan- 125 130

tages, the form hereinbefore described being merely a preferred embodiment thereof.

I claim:

1. A machine of the class described, comprising a casing equipped with a coin slot and a coin receptacle, a plurality of targets visibly arranged within the casing and having designations associated therewith indicating rewards to be obtained or points to be scored, a driver whereby a coin after being inserted in said slot may be driven at said targets, the coins being retained in visible position outside said receptacle after being driven, means for transferring the coins from such position to said receptacle, and means operable by said last-mentioned means for changing the designations associated with said targets.
2. A machine of the class described, comprising a casing equipped with a coin slot and a coin receptacle, a plurality of targets visibly arranged within the casing and having designations associated therewith indicating rewards to be obtained or points to be scored, a driver whereby a coin after being inserted in said slot may be driven at said targets, and coin-controlled mechanism for changing the designations associated with said targets.
3. A machine of the class described, comprising a casing equipped with a coin slot and a coin receptacle, a plurality of targets visibly arranged within the casing and having designations associated therewith indicating rewards to be obtained or points to be scored, a driver whereby a coin after being inserted in said slot may be driven at said targets, a coin pocket adapted to receive a successfully driven coin, and mechanism operable by means of a coin in said pocket for changing the designations associated with said targets.
4. A machine of the class described, comprising a casing equipped with a coin slot and a coin receptacle, a plurality of visible targets in the casing each having a coin pocket associated therewith, means whereby the coins may be directed towards said targets by the operator, a legend-bearing cylinder mounted adjacent said targets a part only thereof being visible, and mechanism operable by means of a coin in a said pocket to rotate said cylinder to change the legends associated with the targets.
5. A machine of the class described, comprising a casing equipped with a coin slot and a coin receptacle, a plurality of visible targets in the casing each having a coin pocket associated therewith, means whereby the coins may be directed towards said targets by the operator, a legend-bearing cylinder mounted adjacent said targets a part only thereof being visible, mechanism operable by means of a coin in a said pocket to rotate said cylinder to change the legends associated with the targets.

associated with the targets, operation of said mechanism also discharging the coin into said receptacle.

6. A machine of the class described, comprising a casing equipped with a coin slot and a coin receptacle, a plurality of visible targets in the casing each having a coin pocket associated therewith, means whereby the coins may be directed towards said targets by the operator, a legend-bearing cylinder mounted adjacent said targets a part only thereof being visible, mechanism operable by means of a coin in a said pocket to rotate said cylinder to change the legends associated with the targets, operation of said mechanism being necessary to discharge the coin into said receptacle.

7. A machine of the class described, comprising a casing equipped with a coin slot and a coin receptacle, a plurality of visible targets in the casing each having a coin pocket associated therewith, means whereby the coins may be directed towards said targets by the operator, a legend-bearing cylinder mounted adjacent said targets a part only thereof being visible, mechanism operable by means of a coin in a said pocket to rotate said cylinder to change the legends associated with the targets, said mechanism including a ratchet on said cylinder and a pawl operable from the exterior of the machine when there is a coin in one of said pockets.

8. A machine of the class described, comprising a casing, a plurality of visible targets in said casing, a coin slot, means whereby coins inserted in said slot may be directed by the operator towards said targets, a legend-bearing member adjacent said targets, a part only thereof being visible, coin pockets adapted to receive the coins which reach said targets, a plurality of apertured bars beneath said pockets, the apertures thereof being normally out of registration and one of said bars being movable by the operator to bring its apertures into alignment with the apertures of another of said bars, the coin then entering aligned apertures and interlocking said bars, movement of the bars together carrying said coin to a point of discharge into the coin receptacle, and means operable by such movement of said bars for moving said legend-bearing member to change the legends presented to view thereby.

9. A machine of the class described, comprising a casing equipped with a coin slot and a coin receptacle, said casing being provided with a glass front, a coin slot, a plurality of coin pockets disposed one above the other behind said glass front near the upper portion of the casing and opening horizontally, a plurality of coin pockets opening vertically in the lower part of the casing at the bottom of said glass front, a driver

whereby a coin inserted in said slot may be impelled through the space behind said glass front towards said coin pockets, means whereby the coins from the vertically opening pockets in the lower part of the casing may be discharged into the coin receptacle, and means operable by said last-mentioned means for discharging the coins from said horizontally opening pockets in the upper 10 part of the casing.

In witness whereof, I hereunto subscribe my name to this specification.

FRED L. MILLS.

CERTIFICATE OF CORRECTION.

Patent No. 1,805,838.

Granted May 19, 1931, to

FRED L. MILLS.

It is hereby certified that the name of the assignee in the above numbered patent was erroneously written and printed as "Milk Novelty Company", whereas said name should have been written and printed as Mills Novelty Company, as shown by the records of assignments in this office; and that the said Letters Patent should be read with this correction therein that the same may conform to the record of the case in the Patent Office.

Signed and sealed this 4th day of August, A. D. 1931.

(Seal)

**Wm. A. Kinnan,
Acting Commissioner of Patents.**
